Primary Examiner — Omeed Agilee

(57) **CLAIM**

The ornamental design for an assay card hinge, as shown and described.

DESCRIPTION

FIG. 1 shows a top perspective view of an assay card hinge in an open configuration accordance with the present invention;

FIG. 2 shows a top view thereof;

FIG. 3 shows a bottom view thereof;

FIG. 4 shows a front view thereof;

FIG. 5 shows a rear view thereof;

FIG. 6 shows a right side view thereof;

FIG. 7 shows a left side view thereof;

FIG. 8 shows a top perspective view of the assay card hinge in a closed configuration accordance with the present invention;

FIG. 9 shows a top view thereof;

FIG. 10 shows a bottom view thereof;

FIG. 11 shows a front view thereof;

FIG. 12 shows a rear view thereof;

FIG. 13 shows a right side view thereof; and

FIG. 14 shows a left side view thereof.

The dashed broken lines in the drawings depict environmental subject matter and form no part of the claimed design. The dot-dash-dot broken lines in the drawings depict the boundaries of the claimed subject matter and form no part of the claimed design.

1 Claim, 12 Drawing Sheets
